(21) Appl. No.: **29/134,707**

The ornamental design for a vacuum bottle, as substantially shown and described.

(22) Filed: **Dec. 28, 2000**

DESCRIPTION

(30) **Foreign Application Priority Data**

Jul. 18, 2000 (JP) 2000-019703

FIG. 1 is a perspective view of a vacuum bottle according to the invention;

(51) LOC (7) Cl. **07-01**

FIG. 2 is a top plan view thereof;

(52) U.S. Cl. **D7/608**

FIG. 3 is a front vacuum bottle view thereof;

(58) **Field of Search** D7/510, 511, 605,
D7/608; 215/12.1, 12.2, 13.1; 62/457.1,
457.3, 457.7; D9/500, 503, 504, 538; 220/592.27

FIG. 4 is a rear vacuum bottle view thereof;

(56) **References Cited**

FIG. 5 is a bottom plan vacuum bottle view thereof;

U.S. PATENT DOCUMENTS

FIG. 6 is a right end vacuum bottle view thereof;

D333,268 S * 2/1993 Arlinghaus et al. D9/538

FIG. 7 is a left end vacuum bottle view thereof; and,

FIG. 8 is a sectional referential view of the vacuum bottle shown in FIG. 2 take along line **8—8**.
